UNITED STATES PATENT OFFICE

BRUCE J. DAVIDSON, OF MARSEILLES, ILLINOIS, ASSIGNOR TO NATIONAL BISCUIT COMPANY, OF NEW YORK, N. Y., A CORPORATION OF NEW JERSEY

STITCHING MACHINE

Application filed March 31, 1926. Serial No. 98,734.

This invention relates to an improved box-stapling or -stitching machine.

It is an object of the invention to provide a device of this character which will operate at high speeds and with a minimum of noise and vibration.

A further object of the invention is that of furnishing a machine of this type the parts of which will be relatively few in number and simple in construction so that the machine may be operated over relatively long periods of time with freedom from mechanical difficulty.

Another object is that of constructing a stapling or stitching machine which will be entirely automatic in operation and in which, in the event that a cessation in the feeding of the work occurs, the operative functions of the machine will cease; and, further, in which, if through some unforeseen contingency a jamming of the work would be likely to occur, the machine will automatically allow for this condition so that no breakage of the parts will result.

Still another object is that of providing a stapling or stitching machine in which certain of the parts heretofore regarded as necessary will be eliminated, and in which such mechanism as is provided will be susceptible of adjustment to such an extent that widely varying conditions of work may be accommodated in a single machine.

Other objects of the invention will in part be obvious and will in part appear herein-after.

The invention accordingly comprises the features of construction, combination of elements and arrangement of parts which will be exemplified in the construction hereinafter set forth, and the scope of the application of which will be indicated in the claims.

For a fuller understanding of the nature and objects of the invention reference should be had to the following detailed description taken in connection with the accompanying drawings, in which:

Figure 1 is a side elevation of one form of machine embodying the construction of the present invention, certain of the parts

being broken away to disclose the underlying mechanism;

Fig. 2 is an end view thereof;

Fig. 3 is an enlarged side elevation of the stapling or stitching head;

Fig. 4 is a fragmentary partly sectional side elevation of a safety stop-bar;

Fig. 5 is a similar view showing the mechanism which controls the feeding of the wire;

Fig. 6 is a plan view of the feeding mechanism;

Fig. 7 is a fragmentary side elevation thereof;

Fig. 8 is a transverse sectional view taken along the lines 8-8 and in the direction of the arrows of Fig. 7;

Fig. 9 is an end view of the head shown in Fig. 3;

Fig. 10 is a sectional view of the parts as shown in Fig. 9 and illustrating the same in a different position;

Figs. 11 and 12 are partly sectional plan views of the head, the parts in the former figure being shown separated; these views being taken along the lines 11-11 and 12-12 of Fig. 3;

Figs. 13 and 14 are enlarged fragmentary sectional views of the staple-forming and -driving mechanisms and illustrating the same in different positions;

Fig. 15 is a sectional view taken along the lines 15-15 and in the direction of the arrows of Fig. 12;

Fig. 16 is a partly fragmentary plan view of the stitching bar with the clinching blocks in position therein; and

Fig. 17 is a transverse sectional view taken along the lines 17-17 and in the direction of the arrows of Fig. 16.

With primary reference to Figs. 1 and 2, the numeral 20 indicates the base of the machine, which supports a deck 21, as well as U-shaped brackets 22 which have their upper arms overhanging this deck and supporting a bar 23. Carried upon standards 24 and above the bar 23 is a shaft 25, with which various operating mechanisms, hereinafter described, are connected. Mounted below the deck 21 are pairs of transversely-

extending shafts 26 and 27, a shaft 28 being provided between the innermost shafts of the pairs 26 and 27, and preferably in line with the uppermost shafts thereof. The deck of the machine is formed with pairs of grooves 29, the first of which extends parallel to the other and longitudinally of the machine and terminates at a point slightly beyond the shaft 28; the second pair of these grooves being slightly offset with respect to the first-named pair and extending from a point in advance of the shaft 28 to the rear of the deck 21. Mounted one within each of these grooves is a conveyor, preferably of the nature of a sprocket chain 30, one pair of these conveyors passing around sprockets 31 associated with the shafts 26 and 28, and a second pair of these chains passes around sprockets associated with the shafts 27 and 28.

In order to operate these conveyors, as well as the shaft 25, a motor 32 may be suitably mounted upon the frame of the machine and provided with a pinion 33 which meshes with a pinion 34, in turn driving a gear 35 by means of a pinion 36, the whole providing a reduction train. The gear or pinion 35 is mounted upon a shaft 37, to one end of which a sprocket 38 is secured, the latter being connected with a sprocket 39 associated with the rearmost of the shafts 27 by means of a chain 40. Mounted upon the outer end of the shaft 37 is a bevel gear 41 which meshes with the teeth of a corresponding gear 42 associated with the shaft 25.

Thus, when the motor is operated it will be obvious that the chains 30 will be driven to run within the grooves 29 and towards the rear end of the machine, and, likewise, the shaft 25 will be rotated.

Each of the chains 30 is provided with lugs 43, which extend beyond the outer edges thereof and, consequently, above the upper face of the deck 21, so that an object resting upon this deck will be moved longitudinally of the machine. The lugs upon the different pairs of conveyors are so arranged or timed that an object placed upon the forward end of the deck will be moved rearwardly to a point slightly beyond the vertical plane occupied by the shaft 28. Thereupon, and during the continued operation of the machine, it will come to rest and will not continue its movement towards the rear end of the machine until the lugs of the rear conveyor contact with its rear edge.

The article (in the present instance, a box blank) is stitched or stapled immediately after its disengagement by the lugs of the first conveyor. In order to insure against the momentum of the article carrying it past this station, a stop is provided. This member may conveniently embody a construction such as is shown in detail in Fig. 4, in which it will

be noted that a bar 44 is provided which has an extension 45 rockingly secured to its lower end, this extension carrying a contact finger 46 and being maintained normally in alignment with the bar body by means of a spring 47 associated with its body and bearing against the forward edge of the extension 45 to a point beyond that at which it is pivotally associated with the bar proper. This member may be mounted for sliding movement in a guideway 48, and a cam 49 mounted upon the shaft 25 may cooperate with the upper bar end in order to produce a reciprocation of this element to such an extent that its lower end will be projected to a point intersecting the path of travel of an object moving over the deck 21. The timing of the parts is such that this projection occurs when the box which is being moved by the forward conveyor reaches a point at which this conveyor is just moving out of operative contact with the article, and the retraction of the finger 46 and associated parts is effected prior to the time at which the lugs associated with the rearmost conveyor engage the rear edge of the article to be moved.

The present machine is particularly adapted for use in the stapling or stitching of cardboard boxes. These members are initially blanked out of suitable material and are provided with score lines, subsequently to which they are bent so that they remain in collapsed condition and occupy a minimum of space until they are ready for use. Thus, in the present machine to which these collapsed blanks are fed, a stitching bar 50 of usual construction is provided which extends longitudinally of the deck 21 from a point adjacent the forward end of the same to a point preferably to the rear of the stop provided by the mechanism described in the preceding paragraph. This stitching bar serves as a guide for the blanks placed upon the deck of the machine at the forward end as fed to the conveyor and carries an opener 51, which, as the blank is moved rearward by the first conveyor, serves to partially open or extend the upper wings or flaps of the folded blank. A presser foot 52 may be associated with the bar 23 and arranged in the path of travel of the blanks, in which position it serves to press the upper portions thereof into proper contact with respect to each other and with the upper face of the stitching bar. Immediately to the rear of this foot is the working head of the machine, by means of which, in a manner hereinafter described, the adjacent flaps are secured to each other, and at this time it will be noted that a roller 53 is arranged in advance of this foot and is elevated and rotated by frictional contact with the blank in its passage along the stitcher bar; the purpose of this element being hereinafter brought out.

The stitching operation in a mechanism of this character is preferably accomplished by

the use of staples, which are caused to penetrate the upper parts of the blank being operated upon in order to retain the same against movement with respect to each other. 5 These staples are preferably formed within the machine, and to this end suitable reels of wire (not shown) are mounted upon the machine frame and the free ends 54 of the wires are each threaded within a groove 55 formed in the periphery of a pulley 56, the wire being retained in this position by the use of a disk 57 rotating in synchronism with the pulley and having its edge knurled and extending into the groove thereof. In order 10 to effect a simultaneous movement between the pulley and disk, the former may form an integral part of a gear 58, and the latter may likewise form a part of a gear 59, these two gears being rotatably mounted upon a 15 common support and with their teeth in mesh. At this time it will be observed that the shafts supporting the pulleys are each preferably provided with an eccentrically disposed outer end portion 60, and arms 61 20 are associated with the inner ends thereof. Springs 61' are attached to these arms and serve to shift the eccentric portions 60 of the pulley-supporting shafts to a point at which the periphery of the disks 57 extends 25 to a maximum depth into the grooves 55. As a result the wire will at all times be firmly engaged between these members so that a positive feeding will be assured, and this will be true even though the wire might vary in 30 diameter. Wire-feeding units of this nature are provided in a number corresponding to the number of stitching or stapling members associated with the machine head, and all of these units are driven by a shaft 62, the ends 35 of which are suitably supported by brackets 63, the body thereof extending longitudinally of the machine and through openings in plates 64, which latter are disposed at right angles to the bar 23 and have their inner 40 ends extending at an angle of preferably 45° to their bodies, these ends providing the mounting for the wire-feeding units aforescribed. The shaft 62 carries gears 65, the teeth of which engage the teeth of the gears 45 59. As a consequence, when the shaft is rotated each of the units will be operated to feed wire to the staple-forming and -driving apparatus, the amount of feed being equal to the length of wire required for the forming 55 of one staple. While the gears 69 and 65 may be of any suitable form, for example, bevel gears, thin, flat spur gears as here shown are preferred, since the spaces in which these gears may be disposed are relatively small and the flat spur gear of the character illustrated require less space in an axial direction than bevel gears.

It is also to be seen that the angle of 45 degrees by which the inner ends of plates 64 60 meet their bodies may be varied at will so

long as the angular disposition is less than a right angle, the angular disposition determining the direction at which the staples are inserted in the blanks being stitched as hereinafter described; the angular disposition 70 permitting a greater amount of stitching to be done within a given space on the blank without weakening the same than if a horizontal or vertical stitching had been placed in the blank.

In order to rotate the shaft 62 the shaft 25 carries a cam 66, which cooperates with the roller 67 of a pusher rod 68, the lower end of which is carried by a rocker arm 69 loosely encircling the shaft 62. Adjacent the point 75 of connection of the arm and rod a spring-pressed pawl 70 is mounted, and this pawl 80 engages the teeth of a ratchet 71 keyed to the shaft 62. It will be obvious that as the shaft 25 rotates the rod 68 will be reciprocated, due to the contact between the roller 67 and the cam 66, which contact is maintained by a spring 72. As a consequence, the pawl and ratchet will have lost motion as well as simultaneous movement, and this latter movement 85 will occur once to each revolution of the shaft, thus driving the wire-feeding apparatus in the manner aforescribed.

In order to prevent a feeding of wire in the event of a cessation of feed of the blanks, without, however, rendering it necessary to stop the machine, the roller 53 is mounted upon an arm 73, which is rockingly supported as at 74 and is connected by means of a link 75 with a rocker arm 76 mounted upon the shaft 62. This rocker arm has its body extending materially beyond the axis of this shaft and terminates in a shoulder 77, which is movable to a point at which it will engage the pawl 70 to prevent the same from coming 90 into contact with the teeth of the ratchet 71. Thus, while normally the shaft 62 is rotated, as aforescribed, it will be understood that if a blank is not riding over the upper face 95 of the stitcher bar at the moment when the wire is about to be fed, the roller 53 will remain in contact with the stitcher bar, and, accordingly, the arm 73 will not rise, so that the shoulder portion 77 of the rocker arm 76 will engage the pawl 70, and the latter will 100 not be capable of operatively engaging the ratchet, and no feeding of the wire can occur. If, however, as has been shown in Fig. 5, a blank is moving along the stitcher bar no interference with the feeding operation will 105 occur.

Arranged adjacent the wire-feeding units is the working or stitching head of the machine, which in the present instance includes a cross-bar 78 carrying a plurality of downwardly-extending bars 79, upon which spring-pressed trip members or latches 80 are rockingly mounted. Slidably mounted in advance of the forward faces of these bars are a corresponding number of staple-forming 110

bars 81, which have their lower ends terminating in a pair of arms 82, the inner faces of which are grooved as at 83. The upper ends of the bars 81 are notched as at 84, and both sets of bars 79 and 81 are mounted in a block 85 providing guideways therefor. Each of the guideways is formed with an opening for the passage of the wire, and anvil blocks 86 are mounted upon spring arms 87 to extend into these guideways and to occupy positions between the arms 82 of the staple formers when the latter are in elevated position. These blocks are notched as at 88, and when in the position previously specified the notches lie in line with the wire openings formed in the walls of the guide block. The bars 79 extend to a point beyond the base of the arms 82, and each of these bars at these points carries a staple-driving portion 89 which extends into the space between these arms. The upper edge of the block 86 is in each instance beveled as at 90, and when engaged by the member 89 it will be obvious that the block will be swung to the position shown in Fig. 15.

Following the operation of one of the head units, and assuming that the wire has been fed through the opening of the block 85 and that the operating head is in its elevated condition, this wire will enter the notch 88 of the anvil 86 and will extend across the space between the walls of the guideway. If now the bars 79 and 81 are moved downwardly the arms 82 will have their outer ends engaged by those portions of the wire which extend beyond the side faces of the anvil, causing a shearing of the wire and a bending of the ends of the same downwardly until, finally, these ends assume a position at right angles to that portion of the wire which remains in the notch 88, and these ends consequently come to lie within the grooves 83,—the preceding operations having been shown in Figs. 13 and 14. Thereupon the driving member 89 will contact with the beveled upper surface 90 of the anvil, forcing the same into the position shown in Fig. 15, and, as a consequence, the formed staple will move out of engagement with the notch 88 and be supported wholly within the grooves of the arms 82, as has been shown in the figure last mentioned.

In order to effect the aforescribed movement of the bars it will be noted that operating cams or strips 91 are associated with the member 85 providing the guideways. Initially, as the bars 79 move downwardly, the ends of the latches 80 engage with the outermost portions of the bars 81, and these elements move downwardly in unison. After the wire has been sheared and formed into a staple, that portion of the latch which extends beyond the side edge of the bar 79 will engage with an operating strip or cam 91, as has been shown in Fig. 14; thereupon, the bar 79 will

be free to continue its downward movement and move downwardly with respect to the bar 81, the lower end of which is resting adjacent the upper face of the stitcher bar and in contact with the flaps of the blank which it serves to hold in position. The staple driver 89 will move downwardly with the bar 79, and the latch will ride into the notch 84 of the bar 81. As a consequence, a staple will be moved downwardly within the grooves 83 until its lower ends come into contact with the flaps of the blank and penetrate the same.

Adjacent the operating head the stitcher bar 50 carries clincher blocks 92, as has been shown in Figs. 16 and 17, these blocks being adjustable within the bar and normally retained against movement preferably by the use of set screws 93. Thus, when the ends of the staples penetrate the flaps of the box blank they come into contact with the clincher blocks and are diverted by these elements to extend at right angles to the path of travel given them by the driving members 89, it being understood that one clincher block is provided for each unit of the operating or stitching head and that they are accurately aligned.

At this time it will be noted that the groups of bars 79 are so arranged that the staples will have their upper portions parallel to the faces of the angular end portions of the plates 64 and the lines of feed of the wires which are being moved by the feeding units. As a consequence, it will never be necessary for the wire to traverse an obtuse or acute bend, and thus the likelihood of deformed staples being produced will be prevented. Furthermore, by this arrangement it is possible to group a maximum number of staple-forming and -driving units in a minimum amount of space. The operating head is actuated in any desired manner; for example, cams 94 may be associated with the shaft 25 and present track portions, within which rollers 95 carried by the upper ends of arms 96 move, the lower ends of these arms being attached to the bar 78. Obviously, as the cams rotate the bar 78 will move downwardly in order to move the bars 79 and 81 in the manner aforescribed. In the upward movement of the parts a bar 79 will be retracted until the upper edge of the driving member 89 engages the base of the bar 81 between the arms 82, at which point both bars will move in unison, it being understood that the initial movement of these elements with respect to each other allows the lower ends of the latch-members to swing clear of the notch portions 84 of the bars so that the parts will be reset. In order to cushion the upward movement of these elements, and particularly the bars 81, the latter may carry rods 97, with which springs 98 are associated, these springs extending through openings in a guide bar 99 supported by the machine frame. Thus it is unnecessary to employ a

multiplicity of clutches or other mechanism for individually operating the staple-forming and -driving units, but, rather, the entire head embracing these elements is reciprocated to operate them in unison.

In a machine of this character, with the conveyors properly timed, and with a suitable number of staple-forming and -driving units embodied in the stitching head, the clincher blocks are adjusted to exactly the position which will assure a perfect clinching operation. Thereafter the motor is set in operation, which results in a driving of the conveyors and the shaft 25. While the working head is now reciprocating no operative result is reached, for the reason that no wire is being fed to the staple-forming units. As previously stated, this will occur due to the fact that the roller 53 occupies its lowermost position, as no cartons are passing along the stitching bar. As a consequence, the pawl associated with the pusher rod 68 will not operatively engage the ratchet 71 secured to the shaft 62, and, accordingly, the wire-feeding units will not operate.

Upon box blanks being properly fed to the deck of the machine, the first conveyor will move the same so that they are operatively engaged by the opener and their upper portions come to ride over the stitching bar 50 against which they are firmly pressed. Obviously, the wire-feeding units will now operate, and it will be appreciated, as previously brought out, that, due to the angular disposition of these units and the manner in which the staple-forming and -driving units are disposed in relationship thereto, the wire will not have to traverse any bends, and, consequently, any difficulties in this connection are avoided. The box-blank will come to rest in proper position below the operating head, and any tendency of the blank to pass this station incident to its momentum will be avoided by means of the stop provided by the finger 46 associated with the bar 44. If for some unforeseen reason the work being operated upon should become jammed at this point, no breakage of the machine parts will occur even though they continue to operate, for the reason that under such conditions the pressure against the finger 46 will become sufficiently acute to cause the extension 45 of the bar to be rocked around its point of pivotal mounting, allowing a clear passage for the work regardless of the position of the working parts of the machine; it being obvious that under these conditions the proper cycle of operation will automatically reestablish itself—it being only necessary that an operator again return the finger 46 to a position in line with the bar body 44. In any event, during that instant when the blank is at rest the stitching or stapling head will operate to secure the upper flaps thereof to one another. Subsequently, the second con-

veyor will engage the work and move it toward the rear end of the machine where it may be automatically or manually removed from the deck 21.

It will be understood that in a machine of this character the mechanism may be operated at a high speed without the necessity of any automatic throw-out clutches or complicated apparatus. Under normal operation the stitched or stapled work will now be engaged by the rearmost conveyor and carried to the rear end of the machine, where it may be automatically or manually removed from the deck.

Thus, among others, the objects of this invention have been accomplished, and since certain changes may be made in the above construction, and different embodiments of the invention could be made, without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described and all statements of the scope of the invention which as a matter of language might be said to fall therebetween.

Having described my invention, what I claim as new and desire to secure by Letters Patent is:

1. A stapling machine, including a deck, a pair of conveyors for moving articles over said deck, means whereby an article is operatively disengaged from one of said conveyors prior to its operative association with the second of the same, and a stapling head positioned over the second and adjacent the first of said conveyors and acting upon said articles during such interval.

2. A stapling machine, including a deck, a pair of conveyors associated with said deck, elements associated with said conveyors and engaging articles to move the same along said deck, means for continuously moving said conveyors, said conveyors being so timed that the engaging elements of one of the same move out of contact with an article prior to the engagement of said article by the elements of the second conveyor, and a stapling head positioned over the second and adjacent the first of said conveyors and operating upon said article during the interval of non-engagement.

3. A stapling machine, including a deck formed with grooves, conveyors movable within said grooves, elements associated with said conveyors for engaging and moving articles along said deck, means for continuously moving said conveyors, the elements of one of said conveyors disengaging from said article prior to the engagement of the latter by the elements of the second con-

veyor, and a stapling head positioned over the second and adjacent the first of said conveyors, and operating upon said article during said period of disengagement.

5. A stapling machine, including, in combination, a stitching bar, means for feeding work thereover, a single head, and means for reciprocating said head, said head comprising a plurality of staple-forming and -driving units arranged immediately adjacent each other, certain of said units forming a fixed part of said head and moving in unison therewith and in synchronism with each other whereby upon said head being operated a plurality of staples will be formed and driven.

20. A stapling machine, including, in combination, a stitching bar, means for feeding work thereover, a working head, means for operating the same, said working head comprising a plurality of staple-forming and -driving units, said units being disposed at an angle of less than 90° to the direction of feed of the work.

25. A stapling machine, including, in combination, a stitching bar, means for moving articles to be stitched over said bar, a head, means for operating the same, said head comprising a plurality of units each including staple-forming and -driving elements arranged at an angle of less than 90° to the direction of movement of the articles being stitched, and feeding mechanism for supplying wire to said units, said mechanism being arranged parallel to said units whereby said wire is fed in a substantially straight line thereto.

40. A stapling machine, including a stitching bar, a working head cooperating therewith, feeding means for supplying wire to said head and comprising a pair of cooperating rotatable members engaging the wire, means for driving said members, said members being disposed adjacent said head and at an angle of less than 90° to the longitudinal axis of the machine.

45. A stapling machine, including, in combination, a deck, a plurality of article-moving conveyors associated with said deck, a staple-forming and -driving head, means for actuating said mechanism to cause one of said conveyors to move an article to a point adjacent said head, means to temporarily prevent a further movement of said article, means for actuating said head upon said article ceasing to move, means whereby said article is subsequently engaged by a second of said conveyors to move the same towards the rear end of the machine, and means for continuously driving said conveyors.

55. A stitching machine, including a pair of conveyors having their inner ends overlapping, means for constantly driving said conveyors, means for moving an article by means of one of said conveyors to a position adja-

cent the inner ends of both conveyors and disconnecting said article from said first conveyor, said article thereupon assuming a position of rest, a stitching head operating upon said article, and said second conveyor subsequently engaging said article to move the same away from said stitching head.

70. 10. A stitching machine, including a pair of conveyors having their inner ends overlapping, a shaft supporting and common to both of the inner ends of said conveyors, means for constantly driving said conveyors, a stitching head arranged adjacent the overlapping portions of said conveyors, one of the latter engaging an article and bringing it to a position adjacent the inner end thereof, and thereupon disconnecting from said article to cause the latter to assume a condition of rest, means for operating said head to stitch said article, and means for operatively connecting said article thereupon to the second conveyor to move said article from a position adjacent said stitching head.

75. 11. A stitching machine, including a pair of conveyors, article-engaging elements forming a part of the same, means for constantly driving both of said conveyors in substantial synchronism, the inner ends of said conveyors overlapping, a stitching head arranged adjacent the point of overlapping of said conveyors, an article being moved by the engaging elements of one of said conveyors to a position adjacent said head and being thereupon automatically disconnected therefrom, means for operating said stitching head, the article-engaging elements of said second conveyor being timed thereafter to engage said article to shift the same away from said head.

80. 12. A stitching machine, including, in combination, a head, means for operating the same, means for feeding articles to be stitched to said head, a stop arranged beyond said head for arresting the travel of an article, and means for reciprocating said stop, the said stop comprising a pair of sections swingingly connected to each other, and a spring member rigidly secured to one of said sections and bearing against the other of the same to normally maintain both in aligned position with respect to each other.

85. 13. A stitching machine, including article-feeding means, a staple-forming and -driving head comprising, in combination, a slidably-mounted staple-forming bar having a notched lower end forming arms, an anvil block having a horizontally-disposed notch and extending between said arms, a spring arm mounting said anvil, means for feeding wire to notch of the latter, a second bar slidably mounted with respect to the first bar, a pivoted catch connecting said bars, a cam-portion forming a part of said catch, a fixed stop co-operating with said cam-portion during the movement of said bars to disconnect one from the other, means for projecting and retract-

ing said second bar, and means for cushioning the upward movement of said second bar.

14. A stitching machine, including, in combination, a driving shaft extending longitudinally of the machine, a stitching head connected to be reciprocally driven by said shaft, means for rotating said shaft, a pair of conveyors also connected with said shaft to be driven thereby and in synchronism with each other, a wire-feeding mechanism also connected with said shaft and with said head, and means connected with said mechanism for automatically interrupting the feeding of wire in the absence of an article to be stitched by said head.

In testimony whereof I affix my signature:
BRUCE J. DAVIDSON.
